I, Inventor,
Edward Hahnemann,
By John L. Schumacher,
Attala, Mississippi, U.S.A.

UNITED STATES PATENT OFFICE.

EDWARD HAHNEMANN, OF SOUTH KAUKAUNA, WISCONSIN.

RIVET HOLDER.

Application filed February 26, 1921. Serial No. 448,225.

To all whom it may concern:

Be it known that I, EDWARD HAHNEMANN, a citizen of the United States, residing at South Kaukauna, in the county of Outagamie, State of Wisconsin, have invented certain new and useful Improvements in Rivet Holders, of which the following is a specification.

This invention relates to improvements 10 in rivet holders particularly adapted, though not necessarily limited in its use for holding rivets for boiler flue sheets.

Heretofore considerable difficulty and inconvenience has been experienced in riveting 15 boiler flue sheets in position in that portions of the water space are very small and narrow, rendering it difficult to insert a rivet holding bar or jack thereinto, with the result that oftentimes it is necessary to insert 20 several pieces of material or shims to build up a brace between the outer wall or shell of the boiler and the head of the rivet. To overcome these difficulties and objections and to provide an improved rivet holding device 25 which may be readily inserted into a small space and hung upon the flue sheet or other support, is one of the objects of the present invention.

A further object is to provide an improved 30 device of this character which is adapted to be actuated by fluid pressure and which device also operates to draw together the parts that are to be riveted.

A further object is to provide an improved 35 simple, durable, cheap, compact and portable device of this character, which may be readily handled and which will be effective and efficient in operation.

To the attainment of these ends and the 40 accomplishment of other new and useful objects as will appear the invention consists in the features of novelty in substantially the construction, combination and arrangement of the several parts hereinafter 45 more fully described and claimed and shown in the accompanying drawing illustrating this invention and in which—

Figure 1 is a detail front elevation of a portion of a boiler and the flue sheet showing 50 the manner in which this invention is employed.

Figure 2 is a sectional view taken on line 2—2, Figure 1.

Figure 3 is an enlarged vertical sectional view. 55

Figure 4 is a sectional view taken on line 4—4, Figure 3.

Figure 5 is a view taken on line 5—5, Figure 3.

Referring more particularly to the drawing the numeral 10 designates the flue sheet which is to be secured in position and together with the fire box wall 11, and the numeral 12 designates the wrapper sheet of the boiler which extends around or over the fire box. 60 65

The flue sheet 10 is provided with the usual circumferential flange 13, against which the wall 11 rests and to which wall the flue sheet is to be secured. 70

The rivet holder embodies a body portion consisting of telescoping members one of which members 14, is in the form of a cylinder and the other member 15, comprises a piston which operates in the cylinder. 75 The cylinder and piston may be of any desired size and configuration, and are adapted to be held in position by means of suitable frame works so that when fluid is admitted into the space 16, between the piston 80 15 and the head of the cylinder by means of a pipe 17, to which a flexible pipe 18, is connected, the piston and cylinder will be separated. A suitable valve 19, is provided for controlling the admission of the fluid 85 into the cylinder.

The framework for the support of the piston and cylinder may be of any desired structure but preferably embodies two frames or portions. One frame 20, is connected with the cylinder 14, to extend beyond the end thereof and the extremity 21, of the portion 20, is preferably tapered or reduced as shown. Connected with the end 21 of the frame 20 is a hook device 22, the 90 portion 23 of which is swiveled in a suitable bearing 24, so that the hooked extremity 25, may be rotated with respect to the bearing block 24, to move the hook to any desired position. 95

A re-enforcing brace 26, may be provided for the framework 20, if desired. 100

A similar frame 27, is connected with the piston 15, and for that purpose, the piston 15 may be provided on opposite sides thereof with flattened surfaces or portions 28, 5 against which the ends of the frame 27 rest and are secured by means of suitable fastening devices 29. The free extremity of the frame 27, is preferably tapered as at 30 and supports a bearing block 31. An anvil 32, 10 having a rivet seat 33 and a shank 34, is connected with the block 33, preferably by the end of the shank 34, passing through the block and suitable fastening nuts 35, are secured to the shank on each side of the 15 block for holding the anvil in position. A re-enforcing rib 36, may be provided for the frame 27, if desired.

In Figure 3, the rivet holder is shown in its extended position, that is with the piston 15 at substantially the limit of its inward movement into the cylinder 14.

In use, the hook 25, is hooked into one of the flue openings 37, in the flue sheet 10, as shown more clearly in Figure 2, and the 25 anvil 32, is extended over the edge of the wall 11, so as to engage and rest against the head of a rivet 38. When the parts are in this position, fluid is admitted into the space 16, in the cylinder 14, so as to 30 separate the cylinder and piston. This action will tend to draw the hook 25, and the anvil 32 toward each other so as to clamp or hold the head of the rivet 38 against the outside of the wall 11, and the fluid pressure 35 in the cylinder is controlled by the valve 19. When the parts are in this position, the rivet 38 is upset by the use of the ordinary pneumatic hammer operating on the end of the rivet, the anvil 32, holding the rivet in position during this operation.

After the rivet has been thus set, the device may be removed by releasing the fluid from the cylinder 16, which will permit the hook 25 and anvil 32 to be separated, after 45 which the device may be readily detached and placed in position to upset another rivet.

With this improved construction it will be manifest that it is not necessary to place 50 a rivet holding bar or other implement in the water space as the apparatus is hung upon the flue sheet so that the anvil 32 is the only portion of the apparatus which projects into the narrow space thereby rendering it possible to facilitate the upsetting of the rivets.

Obviously the hook 25, may be engaged over any other suitable support when it is desired to rivet other portions of the boiler, 60 such for instance as being engaged over the stay bolts or any other suitable support.

A handle 40, may be provided on the device by means of which it may be readily transported.

65 While the preferred form of the invention

has been herein shown and described, it is to be understood that various changes may be made in the details of construction and in the combination and arrangement of the several parts, within the scope of the claims, 70 without departing from the spirit of this invention.

What is claimed as new is:—

1. A rivet holder embodying a cylinder having an open end, a plunger operating in 75 and extending beyond the cylinder, an anvil connected with and extending beyond the end of one of the parts, a hook like element swiveled to the other part, said hook and anvil being disposed adjacent opposite ends 80 of the said cylinder and plunger, a fluid supply pipe discharging between the plunger and cylinder, and a valve for controlling the supply of fluid, said cylinder and plunger operating under the influence of the 85 fluid to cause the hook like element and anvil to be drawn together.

2. A rivet holder comprising a body structure embodying telescoping elements, a frame connected with each of the elements, 90 the frame of each element extending over and projecting beyond the end of the other element, whereby when the said elements are separated the frames will be drawn together, a supporting hook like element connected 95 with one of the said frames, an anvil connected with the other frame, said hook and anvil being disposed adjacent opposite ends of the telescoping elements, means for delivering a fluid between the telescoping elements to separate them, and means for controlling at will the said fluid.

3. A rivet holder comprising a body structure embodying telescoping elements, a frame connected with each of the elements, 105 the frame of each element extending over and projecting beyond the end of the other element, whereby when the said elements are separated the frames will be drawn together, a supporting hook like element having an axially rotatable connection with one of the said frames, an anvil connected with the other frame, said hook and anvil being disposed adjacent opposite ends of the telescoping elements, means for delivering a 110 fluid between the telescoping elements to separate them, and means for controlling at will the said fluid.

4. A rivet holder comprising a body structure embodying telescoping elements, a 115 frame connected with each of the elements, the frame of each element extending over and projecting beyond the end of the other element, whereby when the said elements are separated the frames will be drawn together, a supporting hook like element connected with one of the said frames, an anvil connected with the other frame, the said hook and anvil being disposed adjacent opposite ends of the said telescoping elements, 120

means for delivering a fluid between the telescoping elements to separate them, means for controlling at will the said fluid, and a handle connected with one of the frames for 5 transporting the device.

In testimony whereof I have signed my name to this specification, in the presence

of two subscribing witnesses, on this 23d day of February, A. D. 1921.

EDWARD HAHNEMANN.
